PIANO ACTION ASSEMBLY

Charles S. Corey, De Kalb, Ill., assignor to The Wurlitzer Company, Chicago, Ill., a corporation of Ohio
Filed June 19, 1963, Ser. No. 288,993
22 Claims. (Cl. 84—240)

This invention relates generally to pianos and analogous musical instruments and relates more particularly to action mechanisms for electronic pianos of the type utilizing percussively actuated reeds as the tone generators.

An assembly known as an action mechanism is conventionally employed in stringed pianos for transmitting actuating force from each key lever to its associated string. Electronic pianos of the type utilizing vibratile reeds instead of strings as the tone generators also incorporate these action mechanisms for actuating purposes. Ordinarily, a horizontal or grand piano type of mechanism is used. However, the vibratile reeds of an electronic piano need be struck only a comparatively light blow for actuation; and, therefore, the hammers used in action mechanisms for an electronic piano are fashioned to be small, relatively lightweight elements. Because of their diminutive size and their lightness, the hammers for electronic pianos are incapable of developing any appreciable frictional force upon engaging a relatively stationary member in a glancing fashion. Difficulty in achieving proper backchecking of these hammers has resulted.

Therefore, an important object of the present invention is to provide an improved backchecking arrangement for hammers of the lightweight type.

A more specific object of the invention is to provide a backchecking arrangement in which the hammer and its cooperating fly engage each other in mechanically interlocked relationship after rebound of the hammer.

A more general object of the invention is to provide a new and improved piano operating arrangement.

Another object of the invention is to provide a piano operating arrangement which facilitates separation of the key levers from the assemblage of action mechanisms.

Still another object of the invention is to provide a piano action mechanism which limits the power which is transmitted to the associated vibratile member.

And still another object of the invention is to provide a piano action mechanism incorporating a multiple-element hammer.

Yet another object of the invention is to provide a piano action mechanism that is arranged for easy regulation of the backchecking function.

A further object of the invention is to provide a piano action mechanism which is characterized by the production of sharper tones.

A still further object of the invention is to provide a piano action mechanism that is arranged for easy regulation of the dwell-time.

And a still further object of the invention is to provide a new and improved coupling arrangement for use in pianos and analogous musical instruments.

And a yet further object of the invention is to provide a novel coupling arrangement for use in connecting a damper rod to the damper lever in a piano action mechanism.

These and other objects and features of the invention will become more apparent from a consideration of the following disclosure.

In order that the principles of the invention may be readily understood, several piano operating arrangements, but to which the application is not to be restricted, are shown in the accompanying drawings wherein:

FIG. 1 is a central sectional view taken through an electronic piano structure and showing various arrangements constructed in compliance with the present invention;

FIG. 2 is an enlarged, side elevational view taken in

2

cross-section and showing the coupling arrangement for connecting the damper rod and damper lever of the action mechanism illustrated in FIG. 1;

FIG. 3 is a plan view taken substantially along the line 5 3—3 of FIG. 2;

FIG. 4 is a central sectional view taken through a stringed piano structure showing a key lever and an action mechanism coupled in compliance with the present invention;

FIG. 5 is an enlarged, side elevational view taken in cross-section and showing the coupling arrangement of FIG. 4;

FIG. 6 is a plan view taken substantially along the line 10 6—6 of FIG. 5;

FIG. 7 is a fragmentary view similar to the showing of FIG. 1 but illustrating the position of the parts at the moment of backchecking;

FIG. 8 is an enlarged, side elevational view of a modified action mechanism arranged to incorporate a multiple-element hammer and adjustment means for individually regulating the backchecking action and the dwell time; and

FIG. 9 is a side elevational view of another modified embodiment of the action mechanism of the invention, particularly arranged for ease in regulating the dwell time and the backchecking action.

Referring now in detail to the drawings, specifically to FIG. 1, an electronic piano structure indicated generally by the numeral 20 will be seen to include a front plate 22, a key bed 24, a front rail 26, and a balance rail 28, all of which extend across the electronic piano structure 20. The balance rail 28 is mounted on the key bed 24 to support and fulcrum an appropriate number of piano key levers, such as natural note key lever 30 and sharp note key lever 32; and in compliance with conventional practice, balance rail pins 34 and 36 are driven into the balance rail 28 to upstand therefrom for directing the pivoting action of the natural note key lever 30 and the sharp note key lever 32 respectively. Annular felt washers or punchings 38 are disposed encompassing the balance rail pins between the balance rail and the bodies of the corresponding key levers for cushioning the engagement between the key levers and the balance rail. As is well known, the bodies of the individual key levers are perforated with longitudinally extending slots which are laterally lined with felt to receive the balance rail pins. Moreover, front rail pins 40 and 42 are mounted to the front rail 26 in upstanding relationship to guide the movement of the forward ends of the natural note key lever 30 and the sharp note key lever 32 respectively. Annular felt washers or punchings 44 are disposed about the front rail pins 40 and 42 to cushion the engagement of the key levers and the front rail.

A key cloth or cushion 46 is fastened to the key bed 24 at a position generally underlying the rear end of the piano key levers for resiliently supporting the same; and adjacent the rear end of each piano key lever, there is mounted a capstan screw 48 which is used in transmitting operating force from the corresponding key lever to the interconnected system of links and levers comprising an action mechanism indicated generally by the numeral 50. The capstan screw 48 has a rounded or spherical head 52 and a tool-engageable formation 54 of non-circular section. The head 52 defines an abuttable engagement member acting between the corresponding key lever and the related action mechanism, and the formation 54 facilitates progressive entrance or retraction of the screw 48 from the body of the corresponding key lever for regulating the height which the screw extends above the surface of the key lever and correspondingly the operative relationship between the key lever and the associated action mechanism.

It is important to observe that none of the operating

links or levers of the action mechanism 50 are mounted directly on the corresponding key lever, the only connection between the key lever and its action mechanism being established by the abuttable engagement at the capstan screw 48. This arrangement of the electronic piano structure 20 facilitates removal of the key levers, individually or in mass, without disruption of the relationship of the levers and links in the respective action mechanisms. There is a corresponding facility in the removal of the action mechanisms. As will be recognized, this ease of removal of the various assemblies greatly simplifies both repair and regulation.

Advantageously and in compliance with an important feature of the invention, a whip stop member 56 is mounted on key bed 24 closely rearwardly of the key levers to arrest dropping movement of the elements of the action mechanism upon removal of the key lever. The whip stop member 56 includes a rail 58 that is directly attached to key bed 24 and further includes a vertical plate 60 which is attached to the rail 58 by screws 52. The specific functioning of the whip stop member 56 will be described more fully hereinafter relative to the description of the detailed construction of action mechanism 50.

Continuing with reference to FIG. 1, a vibratile reed 64 is mounted on a reed bar 66 by means of a cap screw 68 and a lock washer 70. The reed bar 66 is mounted in the piano structure 20 at a position spaced above the rear ends of the various key levers, and the reed 64 is cantilevered from the reed bar to be percussively actuated. To produce the desired musical tone, the vibration of reed 64 is converted into electric oscillations which are converted, in turn, into sound by electronic means. In compliance with well known practices, a pickup member, not shown, is associated with the free end of the cantilevered reed 64 to form with the reed a capacitor which varies in capacity in accordance with the vibration of the reed whereby to convert the mechanical oscillation of the reed into electronic oscillations. Desirably, the reeds associated with bass notes and certain of the reeds associated with middle register notes are provided with a small weight 72 attached to the free end of the reed for lowering the frequency of vibration without making the reed unduly large.

In order to damp the reed 64 selectively, a damper lever 74 is swingably mounted to a damper rail 76 by means of a damper flange 78 and a pivot pin 80. A damper head 82 is affixed to the underside of damper lever 74 overlying the reed 64, and the damper head 82 consists primarily of a felt block which may be directed into cushioned engagement with the reed 64. Additionally, a felt pad 84 is mounted on the damper rail 76 confronting the damper lever 74 for providing cushioned engagement between these latter parts. A damper hold spring 85 is attached to rail 76 to contact the lever 74 resiliently and to bias the head 82 toward reed 64 thereby.

Advantageously, the damper rail 76 comprises two similar elements which are interconnected in axial alignment and which are pivotally mounted in the electronic piano structure 20 by means of end shafts 86. At approximately the mid-line of the electronic piano structure 20, a damper rail lift arm 88 is connected to the two portions of the damper rail 76 by means of wood screws 90 and flanges 92. The damper rail lift arm 88 is swingably connected to a damper connecting rod 94 by means of a pivot 96; and the damper connecting rod 94 is coupled to a pedal rod 98 by means of a fitting 100, the key bed 24 being fashioned with an aperture 102 to pass the pedal rod 98 to the pedal mechanism of the piano structure.

A guide housing 104 is mounted on the upper surface of the key bed 24 surrounding the damper connecting rod 94, housing 104 being apertured with a bore 106 which freely passes the rod 94. In order to bias the rod 94 in a generally upward direction and therefore bias the damper head 82 into contact with the reed 64, a

compression spring 108 is disposed about the damper connecting rod 94 between the guide housing 104 and a spring washer 110 that is affixed to the rod 94 by ears 112 radially outwardly extruded from the rod or by similar abutments. If desired, a felt pad 114 may be situated beneath the lower end of the spring 108 in contact with the housing 104. The guide housing 104 is hollowed with a chamber 116 between the bore 106 and the aperture 102 so that a nut 118 may threadedly engage the lower end of damper connecting rod 94 above the fitting 100. The nut 118 defines an adjustable abutment for engaging the roof of chamber 116, nut 118 and the roof of chamber 116 thereby cooperating to define an upstop for the interconnected rods 94 and 98. By varying the position of nut 118 on the damper connecting rod 94, it is possible to adjust the space between the damper lever 74 and the pad 84 whereby to regulate the so-called "lost motion" and thereby adjust the extent of the damping achieved by means of the damper head 82. It will be recognized that lowering of the rod 98 by means of depressing the corresponding pedal rotates the damper rail lift arm 88 in the direction indicated by arrow 120. Correspondingly, the damper rail 76 is pivoted about the shafts 86 in the general direction indicated by arrow 122. Continued rotation of the damper rail 76 in this direction eventually brings the pad 84 into contact with the damper lever 74 to lift the damper head 82 out of contact with the reed 64, in effect "raising the damper."

Returning to a consideration of the means for percussively actuating the reed 64, it is to be recalled that a depression of the forward end of piano key lever 30 is arranged to cause a striking of the reed 64 through the piano action mechanism 50. The action mechanism 50 is mounted in the electronic piano structure 20 by means of a main rail 124. The action mechanism 50 specifically includes a hammer 126 that is generally horizontally disposed and that is mounted on a pivot 128 to swing in an arc between a hammer support rail 130 and a position percussively engaging the vibratile reed 64. This position of the hammer 126 is indicated in broken outline in FIG. 1. The pivot pin 128 is mounted to the main rail 124 by a butt flange 132 and a wood screw 134. The hammer 126 carries a hammer shank 136 at its end opposite the pivot pin 128, hammer shank 136 supporting a felt pad or hammer head 138 at its free end for actual contact with the reed 64. Desirably, a felt pad or rest 140 is secured to the upper surface of hammer rail 130 for cushionedly contacting the under surface of the hammer.

The action mechanism 50 also includes a whip 142 that is pivotally mounted on main rail 124 by a whip flange 144 and a pivot pin 146. The whip 142 swings about a pivot which is both spaced from and rigidly connected to the pivot 128. The swinging of whip 142 is caused by a corresponding tiltable swinging of the corresponding key lever, and the underside of the whip 142 is provided with a felt pad 148 at a position spaced from the pivot pin 146 and overlying the capstan screw 48. A fly 150 of unitary, wooden construction is mounted on the whip 142 by means of a pivot pin 152, the fly 150 including a laterally extending foot portion 154, portion 154 underlying the hammer rail 130. When the action mechanism 50 is mounted independently of the corresponding key lever in the manner shown, it is advantageous to arrange the hammer rail to provide a let-off function as well. Therefore, a capstan screw 156 is arranged to engage the rail 130 in a threaded fashion at a position generally overlying the foot portion 154 of fly 150. Furthermore, and in order to replace the knuckle which is otherwise conventionally provided on the foot portion of a fly member, a felt pad 158 is secured to the upper surface of foot portion 154, and the capstan screw 156 is fashioned with a rounded or spherical head 160 for cooperating with the felted surface of the foot portion 154. The rounded surface of the head 160 cooperates

with the felt 158 in a rolling rather than a sliding fashion. Moreover, the capstan screw 156 incorporates a tool-engageable formation 162 adjacent the head 160 axially inwardly therefrom. The formation 162 is fashioned with non-round section whereby to permit gripping by a tool for adjusting the penetration of the threaded shank of the capstan screw 156 into the rail 130; and arranging the screw 156 for radial access in adjustment has proved particularly advantageous since the head 160 of the screw is relatively inaccessible because of its relationship with the deflected foot portion 154 of the fly 150. A jack spring 164 of the compression type is desirably arranged to act between the whip 142 and the foot portion 154 in order to bias the foot portion into contact with the head of the capstan screw 156.

Because of the generally horizontal disposition of the hammer 126, special means must be provided for directing and controlling the interaction of the fly 150 and the hammer; and in compliance with the invention, these means include a felt-lined pocket or recess 166 which is fashioned in the hammer 126 to open generally toward the head or tip of the fly 150. The tip of the fly 150 is adapted to operate within the pocket 166 between a planar backcheck surface 168 and a fly tip engaging, dwell surface 170. The advantageous incorporation of the whip stop member 56 in the electronic piano structure 20 prevents the head of the fly 150 from escaping its position in the padded pocket 166 when the corresponding key lever is removed from the piano structure. Specifically, the upright plate 60 of the whip stop member 56 abuts 30 the undersurface of whip 142 upon extraction of the piano key lever to preserve the described relationship of the fly and the hammer.

The planar backcheck surface 168 is carried by the hammer 126 in a position facing toward the pivot 128; and in compliance with an important feature of the invention, the backcheck surface 168 is tilted with respect to a plane drawn perpendicular to the longitudinal axis of the hammer when the hammer is in the backchecking position which is indicated in FIG. 7. This inclination or tilting of the backcheck surface situates a lower toe portion 172 of that surface horizontally closer to a vertical line drawn through the pivot 128 than an upper heel portion 174 of the backcheck surface 168. Cooperatively, the fly 150 carries a planar backcheck surface 176 in generally confronting relationship with the hammer backcheck surface 168. The fly backcheck surface 176 is inclined generally with respect to the longitudinal axis of the fly in order to lodge an upper nose portion 178 against the hammer backcheck surface 168 at a position overlying the toe portion 172 when the hammer and the fly are in the backchecking position. The described relationship of the planar hammer backcheck surface 168 and the planar, fly backcheck surface 176 achieves a mechanical catching of the hammer 126 on its rebound from percussively striking the reed 64. In effect, the nose portion 178 develops a dog action with the toe portion 172 of the hammer backcheck surface so as to lock the fly 150 and the hammer 126 together. This is distinguished from the more conventional, frictional type of catching action. It is desirable to provide felt padding on at least one of the planar backcheck surfaces 168 and 176; and in specific compliance with the illustrated embodiment, felt padding is provided on both of these surfaces.

Returning to FIG. 1, the damper lever 74 is seen to be connected to the whip 142 for retraction of the damper head 82 independently of the damper rail lift arm 88. Specifically, an endwise reciprocable damper rod or link 180 is swingably mounted to the whip 142 by a pivot pin 182, pin 182 being situated on the side of whip flange 144 which is opposite the key lever abutment pad 148. The damper rod 180 is connected to the damper lever 74 by means of a coupling unit 184, the coupling unit including a screw 186, a key fork member 188 and a grommet 190. With reference to FIGS. 2 and 3, the screw 186 is seen

5 to include a diametrically slotted head 192 that defines a radially enlarged formation on the damper rod 180. Immediately beneath the head 192, the screw 186 incorporates a smooth-walled shank 194. The grommet 190 is fabricated from a tough resilient material such as rubber and is specifically fashioned to be perforated with a hole 196 that is of greater diameter than the shank 194. The smooth-walled character of the shank 194 cooperates with the relatively greater size of the hole fashioned in the grommet 190 to permit the grommet to receive the shank of the screw 186 in a freely slideable fashion. With this arrangement, it is possible to rotate the damper rail lift arm 88 so as to raise the damper lever 74 without transmitting a concomitant force to the damper rod 180 and thence to the whip 142. Thus, the screw 186 and the grommet 190 serve to decouple the damper rod 180 from the damper lever 74 upon independent retracting movement of the damper lever under the influence of the pedal which is associated with the damper rail lift arm 88.

20 The grommet 190 is provided with a circumferential groove 198, and the key fork 188 is a bifurcated member which includes opposed, resiliently spreadable tines 200 and a stem 202 that comprises an element doubled upon itself. The stem 202 is adapted to engage the end of damper lever 74 in a piercing manner for connecting the key fork 188 to the damper lever, and the respective arms of the doubled stem 202 merge respectively into the individual tines 200. The tines 200 extend from the end of the damper lever 74 to grip the grommet 190 at the circumferential groove 198 thereof, whereby to position the grommet rigidly with respect to the damper lever. The grommet 190 also includes an upper surface portion 204 which abutably engages the undersurface of head 192. This abutting engagement between the head of screw 186 and the grommet 190 achieves a retracting movement of the damper lever 174 under the direction of relative withdrawing movement of the damper rod 180 upon pivoting of the whip 142 to actuate the hammer 126 into percussive engagement with the reed 64. As will be recognized, the retraction of the damper head 82 that proceeds from this movement of the damper lever frees the reed 64 to vibrate when struck by the head of the hammer. In compliance with a feature of the invention, the key fork 188 is fabricated from a spring wire material for resiliently gripping the grommet 190.

35 It is recognized that the action mechanism 50 may be adapted for use in a stringed or mechanical type of grand piano. Similarly, the coupling unit 184 may be modified to attach a key lever to the abstract of an upright piano action. Therefore and turning to a consideration of FIGS. 4-6, a stringed piano structure 206 is shown to include a key bed 208 which supports a plate 210. A balance rail 212 is mounted in turn on the plate 210 to receive a generally vertically disposed balance rail pin 214, balance rail pin 214 being employed in fulcrumming a key lever 216.

40 The key lever 216 is associated with an action mechanism 218 that includes a hammer 220, hammer 220 being connected to a butt 222 for pivotal action toward a piano string, not shown. The action mechanism 218 also includes a fly or jack 224 which is mounted on a whip 226 for actuation by an endwise reciprocable abstract or sticker 228. The fly 224 includes a tip or head 230 that engages a padded surface 232 on the hammer butt 222 for levering the hammer 220 into percussive engagement with the piano string; and in compliance with the present invention, the key lever 216 is connected to the abstract 228 by a coupling unit 234.

45 The coupling unit 234 includes a screw 236, a key fork 238 and a grommet 240; and turning to a detailed consideration of FIGS. 5 and 6, the screw 236 is seen to include a diametrically slotted head 242 and a smooth walled shank portion 244 beneath the head 242. However, the screw 236 differs from the screw 186 by the provision of a radially enlarged formation 245 spaced beneath the head

242, the formation 245 specifically comprising a collar of greater diameter than the shank 244. The grommet 240, like the grommet 190, is perforated with an axially extending bore 246. However, the bore 246 differs from the bore 196 in that it takes a diameter closely approximating the diameter of the shank 244 for grippingly engaging the shank. As would be recognized, the comparatively tight fit between the grommet and the shank of screw 236 cooperates with the radially enlarged formation 245 to fix the grommet 240 against axial movement relative to the screw 236 in the general direction of abstract 228. Of course, the head 242 opposes movement of the grommet in the opposite direction.

The grommet 240 is fashioned with a circumferential groove 248 which receives the opposed and spreadable tines 250 of the key fork 238, the key fork 238 additionally including a stem 252 that piercingly engages the end of key lever 216. The key fork 238, like the key fork 188, is advantageously fabricated from a spring wire material, and the grommet 240 is desirably made from a tough, resilient material, preferably an elastomer such as rubber.

While a particular embodiment of the electronic piano structure of the invention has been thus far shown and described, it should be understood, of course, that the invention is not limited thereto since many modifications may be made. Therefore and in order to further the understanding of the invention, two modified embodiments thereof are illustrated respectively in FIGS. 8 and 9. Since the embodiments of FIGS. 8 and 9 incorporate many elements which are comparable to those found in the embodiment of FIG. 1, like numerals are used to designate like parts, the suffix letter "a" being employed to distinguish those elements associated with the embodiment of FIG. 8 and the suffix letter "b" being utilized to distinguish those elements associated with the embodiment of FIG. 9.

The embodiment of FIG. 8 is particularly characterized by the provision of a multiple element hammer and by the provision of means for adjusting the position of the backcheck and dwell surfaces in the pocket of the hammer. Specifically, the hammer head 138a and the hammer shank 136a are mounted on a first hammer member 254 that is swingably mounted to a second hammer member 256 by a hinge 258. The hammer member 256 is recessed to receive the hammer member 254, and the axis of hinge 258 is disposed parallel to and spaced from the pivot 128a by which the hammer member 256 is mounted to the main rail 124a. A leaf spring 260 is affixed to the hammer member 256 yieldably to contact the hammer member 254 for resiliently restraining the hammer member 254 with respect to the hammer member 256. In addition, the hammer member 256 includes an abutment member 262 that extends a plate or shoulder portion beyond the end of hammer member 254 for engaging a hammer stop rail 264. The hammer stop rail 264 is horizontally spaced from the main rail 124a in approximately horizontal alignment with the hammer flange 132a. A felt pad 266 is affixed to the underside of stop rail 264 for providing a cushioned engagement between the stop rail and the abutment member 262 of hammer member 256.

The multiple element hammer 126a controls the power which is delivered to the reed 64a, protecting the delicate reed and prolonging its life. In operation, the amount of force which a fly transmits to its hammer depends to a large degree on the force transmitted to the corresponding key lever by the player of the instrument. The force transmitted by the hammer to the associated reed varies in a related fashion. However, by the construction shown and described with regard to FIG. 8, the mechanical force transmitted to the hammer is delivered to the stop rail 264; and the hammer element 254 swings in independent, inertial movement into percussive engagement with the reed 64a. This inertial swinging movement of the

hammer 254 is resisted by the spring 260, the spring 260 further acting to return the hammer member 254 into close proximity with the hammer member 256.

While the spring 260 tends to provide some backcheck action, it is advantageous to include the cooperating backcheck surfaces 168a and 176a to prevent the hammer member 256a from "chattering" between the stop rail 264 and the hammer support rail 130a; and in compliance with a feature of the invention, means are provided for adjustably mounting the backcheck surface 168a to the hammer member 256. As has been described, the planar backcheck surface 168a is defined by a felt member; and in order to render the backcheck surface adjustably positionable, this felt part is mounted on a plate 268, plate 268 being affixed, in turn, to a screw 270 that threadedly engages a cooperatively threaded bore formed in depending a heel 272 of the hammer member 256. Oppositely from the plate 268, the screw 270 is fashioned with a diametric slot 274 which defines a tool-engageable formation for use in directing the screw 270 into progressive engagement with the heel 272. As will be recognized, it is necessary to lift the hammer member 256 above the hammer support rail 130a to expose the slot 274 for performing the regulation.

It has been mentioned hereinabove that great power is unnecessary in an action mechanism for an electronic piano; and in order to reduce the power of the piano action and in order to sharpen the tones which are produced, it is desirable to provide means for adjusting the dwell time, that is, the time during which the tip of the fly stays in contact with the hammer after the fly has been actuated by depression of the forward end of the corresponding key lever. The dwell time period begins upon initiation of depression of the forward end of the key lever and ends at the moment of hammer escapement, that is, the moment at which the hammer rises out of contact with the head or tip of the fly. Therefore, an end piece 276 of the felt which defines the dwell surface 176a is attached to a plate or dwell button 278; and plate 278 is connected to a screw 280 that threadedly engages a bore formed in the end of hammer member 256. A diametric slot 282 or other suitable, tool-engageable formation is fashioned on the free end of screw 280, and an appropriately shaped aperture 284 is provided in the main rail 124a to provide access to the slot 282 for use in regulating the position of the felt end piece 276. Advancing or retracting the screw 280 relative to the end of hammer member 256 adjusts the distance along the dwell surface 170a upon which the tip of fly 150a rides prior to escapement. It has been found that proper regulation of the dwell time prevents muffled tones which arise because of the vibrating reed hitting the head of the hammer due to a slow departure of the hammer after initial percussive engagement with the reed. Keen and rapid departure of the hammer from the reed prevents the introduction of spurious harmonics into the oscillatory output from the reed.

The embodiment of FIG. 9 is characterized by the provision of adjustment means for the backcheck surface 168b and the dwell surface 170b both of which are accessible from above. More particularly, the felt part which defines the backcheck surface 168b is mounted on a plate 286 which is connected to a screw 288 having a diametric slot 290 at its free end. In particular accord with the principles of the embodiment of FIG. 9, the screw 288 is angled through the body of hammer 126b in the general direction of the hammer head 138b.

With regard to the dwell surface 170b, the entire felt piece which defines the surface is attached to a substantially L-shaped plate 292 that is connected to a screw 294 having a diametrically slotted free end 296. In specific accord with the principles of the embodiment of FIG. 9, the screw 294 passes through the end of hammer 126b in a generally downward direction whereby to expose the slot 296 to access from above. Such mounting of the

screw 294 avoids the necessity for aperturing the main rail 124b.

The manner in which the present invention may be practiced and the purposes to which it may be put are evident from the foregoing descriptions. In addition, the specific examples herein shown and described are to be considered as being primarily illustrative. Various changes beyond those exemplified will, no doubt, occur to those skilled in the art; and such changes are to be understood as forming a part of this invention insofar as they fall within the spirit and scope of the appended claims.

The invention is claimed as follows:

1. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots; a planar backcheck surface carried by said hammer in a position facing toward said first pivot, said surface being tilted with respect to a plane drawn perpendicular to the longitudinal axis of said hammer to dispose a lower toe portion of said surface horizontally closer to a vertical line drawn through said first pivot than an upper heel portion of said surface when said hammer is in backchecking position; and a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying the toe portion thereof when said hammer and said fly are in backchecking position whereby to lock said hammer against movement toward said vibratile member.

2. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots; a planar backcheck surface carried by said hammer in a position facing toward said first pivot, said surface being tilted with respect to a plane drawn perpendicular to the longitudinal axis of said hammer to dispose a lower toe portion of said surface horizontally closer to a vertical line drawn through said first pivot than an upper heel portion of said surface when said hammer is in backchecking position; a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying the toe portion thereof when said hammer and said fly are in backchecking position whereby to lock said hammer against movement toward said vibratile member; and felt padding on at least one of said backcheck surfaces.

3. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots, said fly including a laterally extending foot portion; a planar backcheck surface carried by said hammer in a position facing toward said first pivot,

said surface being tilted with respect to a plane drawn perpendicular to the longitudinal axis of said hammer to dispose a lower toe portion of said surface horizontally closer to a vertical line drawn through said first pivot than an upper heel portion of said surface when said hammer is in backchecking position; a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying said toe portion thereof when said hammer and said fly are in backchecking position whereby to lock said hammer against movement toward said vibratile member; and a let-off member on said hammer rail including a spherical head confronting the foot portion of said fly to define an abutment for causing pivoting of said fly upon engagement of said head by said foot portion.

4. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots, said fly including a laterally extending foot portion; a planar backcheck surface carried by said hammer in a position facing toward said first pivot, said surface being tilted with respect to a plane drawn perpendicular to the longitudinal axis of said hammer to dispose a lower toe portion of said surface horizontally closer to a vertical line drawn through said first pivot than an upper heel portion of said surface when said hammer is in backchecking position; a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying said toe portion thereof when said hammer and said fly are in backchecking position whereby to lock said hammer against movement toward said vibratile member; and a let-off member threadedly engaging said hammer rail, including a spherical head confronting the foot portion of said fly to define an abutment for causing pivoting of said fly upon engagement of said head by said foot portion and including a tool-engaging formation axially inwardly from said head.

5. In a piano arrangement, the combination comprising: a stationary rail adapted to act as a rest for a hammer; a vibratile member spaced from said hammer rail; a generally horizontally disposed hammer mounted on a first pivot to swing in an arc between said rail and a position percussively engaging said vibratile member; a whip mounted to swing about a second pivot both spaced from said first pivot and rigidly connected thereto; a key lever fulcrumed intermediate its ends and having a formation abutably engaging said whip for actuating the same; a fly mounted on said whip to swing about a third pivot spaced from said first and second pivots; a planar backcheck surface carried by said hammer in a position facing toward said first pivot, said surface being tilted with respect to a plane drawn perpendicular to the longitudinal axis of said hammer to dispose a lower toe portion of said surface horizontally closer to a vertical line drawn through said first pivot than an upper heel portion of said surface when said hammer is in backchecking position; and a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying said toe portion

thereof when said hammer and said fly are in backchecking position whereby to lock said hammer against movement toward said vibratile member.

6. In a piano arrangement, the combination comprising: a stationary rail adapted to act as a rest for a hammer; a vibratile member spaced from said hammer rail; a generally horizontally disposed hammer mounted on a first pivot to swing in an arc between said rail and a position percussively engaging said vibratile member, said hammer having a pocket adapted to receive the tip of a fly; a whip mounted to swing about a second pivot both spaced from said first pivot and rigidly connected thereto; a key lever fulcrumed intermediate its ends and having a formation abuttable engaging said whip for actuating the same; a fly mounted on said whip to swing about a third pivot spaced from said first and second pivots; and a stationary stop member fixed in position beneath said whip and spaced closely therefrom to permit normal operation thereof and to arrest dropping movement thereof upon removal of said key lever, whereby to preserve the location of the tip of said fly in said pocket.

7. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots; a planar backcheck surface carried by said hammer in a position facing toward said first pivot, said surface being tilted with respect to a plane drawn perpendicular to longitudinal axis of said hammer to dispose a lower toe portion of said surface horizontally close to a vertical line drawn through said first pivot then an upper heel portion of said surface when said hammer is in backchecking position; a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying said toe portion thereof when said hammer and said fly are in backchecking position whereby to lock said hammer against movement toward said vibratile member; and means adjustably mounting the hammer backcheck surface to said hammer.

8. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member; a whip mounted to swing about a second pivot spaced from said first pivot; a fly mounted on said whip to swing about a third pivot spaced from said first and second pivots; a planar backcheck surface carried by said hammer in a position facing toward said first pivot, said surface being tilted with respect to a plane drawn perpendicular to longitudinal axis of said hammer to dispose a lower toe portion of said surface horizontally closer to a vertical line drawn through said first pivot then an upper heel portion of said surface when said hammer is in backchecking position; a planar backcheck surface carried by said fly in generally confronting relationship with the hammer backcheck surface, said fly backcheck surface being inclined with respect to the longitudinal axis of said fly to lodge an upper nose portion of said fly backcheck surface against the hammer backcheck surface at a position overlying said toe portion thereof when said hammer and said fly are in backchecking position whereby to lock said hammer against movement toward said vibratile member; and means adjustably mounting the hammer backcheck surface to said hammer, including an adjustment member, a backcheck

plate on one end of said adjustment member, a tool-engageable formation on the other end of said member, and means between said ends for progressively engaging said hammer.

9. In a piano arrangement, the combination comprising: a stationary rail adapted to act as a support for a hammer; a vibratile member spaced from said hammer support rail; a hammer stop rail positioned intermediate said vibratile member and said hammer support rail; and hammer means including a first hammer member mounted on a pivot to swing in an arc between said support rail and said stop rail, said first hammer member having an abutment formation for engaging said stop rail, said hammer means further including a second hammer member pivotally mounted on said first hammer member for movement therewith, said second hammer member being spaced from said stop rail for independent, inertially swinging movement into percussive engagement with said vibratile member.

10. In a piano arrangement, the combination comprising: a stationary rail adapted to act as a support for a hammer; a vibratile member spaced from said hammer support rail; a hammer stop rail positioned intermediate said vibratile member and said hammer support rail; hammer means including a first hammer member mounted on a pivot to swing in an arc between said support rail and said stop rail, said first hammer member having an abutment formation for engaging said stop rail, said hammer means further including a second hammer member pivotally mounted on said first hammer member for movement therewith, said second hammer member being spaced from said stop rail for independent, inertially swinging movement into percussive engagement with said vibratile member; and biasing means resiliently restraining said second hammer member in position with respect to said first hammer member.

11. In a piano arrangement, the combination according to claim 10 wherein said biasing means is a leaf spring fixed to said first hammer member and yieldably contacting said second hammer member.

12. In a piano arrangement, the combination comprising: a stationary rail adapted to act as a support for a hammer; a vibratile member spaced from said hammer support rail; a hammer stop rail positioned intermediate said vibratile member and said hammer support rail; hammer means including a first hammer mounted on a pivot to swing in an arc between said support rail and said stop rail, said first hammer member having an abutment formation for engaging said stop rail, said hammer means further including a second hammer member pivotally mounted on said first hammer member for movement therewith, said second hammer member being spaced from said stop rail for independent, inertially swinging movement into percussive engagement with said vibratile member; and padding means acting between said stop rail and said first hammer member for cushioning the engagement thereof.

13. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member, said hammer having a pocket adapted to receive the tip of a fly; a whip mounted to swing about a second pivot spaced from said first pivot; a fly mounted on said whip to swing about a third pivot spaced from said first and said second pivots; fly tip engaging means disposed in said pocket; and means adjustably mounting said fly tip engaging means to said hammer for regulating the dwell time of the tip of said fly upon actuation thereof.

14. In a piano arrangement, the combination comprising: a stationary rail adapted to act as a rest for a hammer; a vibratile member spaced from said hammer rail; a hammer mounted on a first pivot to swing in an arc be-

tween said rail and a position percussively engaging said vibratile member, said hammer having a pocket adapted to receive the tip of a fly; a whip mounted to swing about a second pivot spaced from said first pivot; a fly mounted on said whip to swing about a third pivot spaced from said first and said second pivots; fly tip engaging means disposed in said pocket; and means adjustably mounting said fly tip engaging means to said hammer for regulating the dwell time of the tip of said fly upon actuation thereof, including a plate, means connected to said plate and progressively engaging said hammer, and a tool-engageable formation on said last mentioned means.

15. In a piano arrangement, the combination comprising: a stationary rail adapted to act as a rest for a hammer; a vibratile member spaced from said hammer rail; a hammer mounted on a first pivot to swing in an arc between said rail and a position percussively engaging said vibratile member, said hammer having a pocket adapted to receive the tip of a fly; a whip mounted to swing about a second pivot spaced from said first pivot; a fly mounted on said whip to swing about a third pivot spaced from said first and said second pivots; fly tip engaging means disposed in said pocket; and means adjustably mounting said fly tip engaging means to said hammer for regulating the dwell time of the tip of said fly upon actuation thereof, including a substantially L-shaped plate, means connected to said plate and progressively engaging said hammer, a tool-engageable formation on said last mentioned means, and resilient padding means on said plate confronting the tip of said fly.

16. In a piano arrangement, the combination comprising: a vibratile member; a damper lever mounted on a first pivot to swing in an abbreviated arc toward and away from said vibratile member; a damper head on said lever for contacting said member selectively to damp the vibration thereof; actuating lever means including an endwise reciprocable damper rod; and coupling means connecting said damper lever to said damper rod for retracting movement of said damper lever directed by relative endwise withdrawing movement of said damper rod and for decoupling said rod from said damper lever upon independent retracting movement of said damper lever, including a radially enlarged formation on said damper rod, a smooth walled shank portion on said damper rod extending a substantial distance beneath said formation, a resilient member disposed generally about a part of said shank portion with a confronting wall spaced from said shank portion for slidably positioning said resilient member on said damper rod, said resilient member having a surface portion abutably engageable with said formation, and a bifurcated member affixed to said damper lever and extending therefrom into gripping engagement with said resilient member.

17. In a piano arrangement, the combination comprising:

5 ing: a vibratile member; a damper lever mounted on a first pivot to swing in an abbreviated arc toward and away from said vibratile member; a damper head on said lever for contacting said member selectively to damp the vibration thereof; actuating lever means including an endwise reciprocable damper rod; and coupling means connecting said damper lever to said damper rod for retracting movement of said damper lever directed by relative endwise withdrawing movement of said damper rod and for decoupling said rod from said damper lever upon independent retracting movement of said damper lever, including a radially enlarged formation on said damper rod, a smooth walled shank underlying said formation, a resilient member perforated with a hole of greater diameter than said shank whereby slidably to receive said shank, said resilient member having a circumferential groove and having a surface portion abutably engageable with said formation, and a bifurcated member affixed to said damper lever and having opposed, resiliently spreadable tines extending therefrom to grip said resilient member at said groove.

10 18. In a piano arrangement, the combination according to claim 17 wherein said tines are of spring material.

19. In a piano arrangement, the combination according to claim 16 wherein said resilient member is fashioned from an elastomer.

15 20. A coupling arrangement for use in pianos and analogous musical instruments comprising: a lever fulcrumed intermediate its ends for transmitting motion to a link; an endwise reciprocable link situated adjacent one end of said lever; connecting means extending from said lever into coupling relationship with said link, including opposed and resiliently spreadable tines, said connecting means further including a separate, tough, resilient member gripped by said tines, said member defining a medial aperture extending therethrough for receiving said link; and means on said link for restricting movement of said resilient member axially of said link.

21. A coupling arrangement according to claim 20 wherein said tines are of spring material.

20 22. A coupling arrangement according to claim 20 wherein said resilient member is fashioned from an elastomer.
